UNITED STATES PATENT OFFICE

CORNELIS FRANCISCUS MARIA VAN BERKEL, OF WASSENAAR, NETHERLANDS, ASSIGNEE TO U. S. SLICING MACHINE COMPANY, OF LA PORTE, INDIANA, A CORPORATION OF INDIANA

SLICING MACHINE

Application filed June 20, 1927, Serial No. 200,245, and in the Netherlands September 10, 1926.

This invention relates to machines for slicing meat and other commodities, and has for one of its objects the provision of a slicing machine in which the work support remains stationary while the slicing knife is moved transversely thereof to sever a slice from material on the work support.

A further object is to provide a power drive for reciprocating said slicing knife relative to the work support and simultaneously rotating the slicing knife.

A further object is to provide a slicing machine which shall be of improved construction and operation.

Other objects will appear from the following description.

The invention is exemplified in the combination and arrangement of parts shown in the accompanying drawings and described in the following specification, and it is more particularly pointed out in the appended claims.

In the drawings—

Fig. 1 is an elevation, with parts in section, showing one embodiment of the present invention;

Fig. 2 is a top plan view of the machine shown in Fig. 1 with the support for the slicing knife shown in section;

Fig. 3 is a diagrammatic view showing one form of releasable connection for the knife reciprocating element;

Fig. 4 is a view similar to Fig. 3 showing a modified form of drive for the reciprocating element;

Fig. 5 is a section of a friction drive forming a part of the construction illustrated in Fig. 4; and

Fig. 6 is an elevation of a modified form of the invention having the motor mounted on the reciprocating support for the knife.

The numeral 10 designates a base or support having a pedestal 11 thereon in the upper end of which a drive shaft 12 is journaled for rotation. The drive shaft 12 is driven by worm gearing 13 from a motor 14 mounted on the pedestal 11. A knife supporting bracket 15 is swung upon the pedestal 11 for reciprocation about the shaft 12 as an axis.

50 The bracket 15 supports a housing 16 in

which sprocket wheels 17, 18 and 19 are mounted. The sprocket wheel 17 is secured to the shaft 12, while the sprocket wheels 18 and 19 are mounted on shafts 20 and 21, respectively, journaled in the housing 16. The slicing knife 22 is secured to the shaft 20. A sprocket chain 23 is trained over the sprocket wheels 17, 18 and 19. It will be apparent that rotation of the shaft 12 will rotate the sprocket wheel 18 and knife 22 thereon irrespective of the position of the housing 16 upon its pivotal support 12. The housing 16 is oscillated upon its support 12 to move the knife 22 past the work support for severing slices by means of a link 24 journaled on a crank pin 25 on the sprocket wheel 19 and having its opposite end pivoted upon a pin 26 mounted in fixed position on the pedestal 11. The bracket 15 may be provided with a slot 27 to permit oscillation of the bracket without interference by the pin 26. Rotation of the sprocket wheel 19 will operate to shift the bracket 15 and housing 16 back and forth between the full line and broken line positions shown in Fig. 1, thus moving the 75 slicing knife 22 past the work support simultaneously with the rotation of the slicing knife, thus severing slices from the material held by the work support.

The work holder comprises a supporting plate 28 mounted to slide on the base 10 in a direction normal to the cutting plane of the knife 22 and has a clamp 29 for securing work thereon. The work holder 28 is fed toward the slicing knife by a threaded screw operated by a ratchet wheel 30 in a well-known manner. The ratchet wheel is actuated by a pawl 31 carried by an arm 32 which is connected by a link 33 with a pivot pin 34 on the bracket 15. The amount of rotation of the ratchet wheel is controlled by a cam 35 which may be adjusted by a lever 36 and operating rod 37.

It is sometimes desirable to rotate the slicing knife without oscillating the supporting bracket therefor, as, for instance, for the purpose of sharpening the knife. One arrangement for producing this operation is illustrated diagrammatically in Fig. 3 in which the link 24 is provided with a longi-

tudinal slot 38 having an offset portion 39 for receiving the pin 26. The pin is held in the offset portion by a screw 40. When it is desired to rotate the knife while the 5 housing 16 is stationary the screw 40 is released and the link 24 is shifted to bring the pin 26 from the offset portion 39 to the longitudinally extending portion of the groove 38. Rotation of the sprocket wheel 10 19 then serves merely to move the link 24 back and forth longitudinally without shifting the housing 16. A similar result may be obtained by mounting the crank pin 25 so as to be operated by a frictional drive, as 15 indicated in Figs. 4 and 5. In this case the crank pin 25 is secured to a friction disc 41 having frictional contact with the sprocket wheel 19, the parts being held in engagement by a spring 42. With this construction the 20 housing 16 may be locked against reciprocation and the sprocket 19 will be rotated relative to the crank pin 25, which will remain stationary. The sprocket 19 in Figs. 3 and 25 4 may be driven from a motor mounted on the casing 16 as in the form of the invention shown in Fig. 6, or from a stationary support as in Figs. 1 and 2.

In the modification shown in Fig. 6, the 30 motor 45 is mounted on a bracket 46 carried by the reciprocating knife support 47. The knife 48 is mounted on a shaft 49 driven by a sprocket wheel 50 over which the sprocket chain 51 travels. A sprocket wheel 52 is provided with a crank pin and link connection, not shown in the drawings, but similar to that of Fig. 1 for oscillating the knife support 47. The knife support 47 shown in Fig. 6 may also be oscillated by means of the crank and pitman connection shown in 35 Fig. 3 if desired, instead of by a straight link as shown in Fig. 1. The sprocket chain 51 is driven by a sprocket 53 journaled at the end of the support 47 opposite the knife 48 and connected with a driving disc 54 which has a frictional driving connection 40 with a drive pulley 55 on the motor 45. In this arrangement the motor 45 is utilized for counterbalancing the weight of the knife 48. The support 47 is pivoted at 56 on the 45 frame member 11.

I claim:—

1. A slicing machine comprising a support, a casing adapted to move relatively to said support and guided by means on said support, a knife having a spindle journaled in said casing, a sprocket fastened to said spindle within said casing, a chain drive for said sprocket, a rotary member within said casing and driven by said chain, a pitman operatively connected at one end to said rotary member and at its other end to a member extending through said casing and attached to said support, and means for actuating said chains to rotate said sprocket and 55 said rotary member.

2. A slicing machine comprising a support, a casing adapted to move relatively to said support and guided by means on said support, a knife having a spindle journaled in said casing, a sprocket fastened to said spindle within said casing, a chain drive for 70 said sprocket, a rotary member within said casing and driven by said chain, a pitman operatively connected at one end to said rotary member and at its other end to a member 75 extending through said casing and attached to said support, and means for actuating said chains to rotate said sprocket and said rotary member, said last mentioned means comprising a sprocket engaging said chain, a shaft upon which said sprocket is rigidly mounted, said shaft extending through said casing and being operatively connected to power means for rotating the 80 same.

3. A slicing machine comprising a reciprocating support, a fixed support, a rotary member on one of said supports, a pitman connected between said rotary member and the other of said supports the rotary movement 90 of said rotary member causing said supports to move relatively to each other, a lost motion connection between said pitman and one of said supports so as to render said pitman connection inoperative when desired, and means for preventing the operation of said lost motion connection, said last mentioned means being adapted to locate in a predetermined position the pivotal connection between said pitman and each of said supports. 100

4. A slicing machine comprising a reciprocating support, a fixed support, a rotary member on one of said supports, a pitman connected between said rotary member and the other of said supports, the rotary movement of said rotary member causing said supports to move relatively to each other, a lost motion connection between said pitman and one of said supports so as to render said pitman connection inoperative when desired, 105 means for preventing the operation of said lost motion connection, said last mentioned means being adapted to locate in a predetermined position the pivotal connection between said pitman and each of said supports, 110 and a motor for driving said rotary member.

5. A slicing machine comprising a reciprocating support, a fixed support, a rotary member on one of said supports, a pitman connected between said rotary member and the other of said supports, the rotary movement of said rotary member causing said supports to move relatively to each other, a lost motion connection between said pitman and one of said supports so as to render said pitman connection inoperative when desired, 120 means for preventing the operation of said lost motion connection, said last mentioned means being adapted to locate in a predetermined position the pivotal connection be- 125 130

tween said pitman and each of said supports, and a motor on said reciprocating support for driving said rotary member.

In testimony whereof I have signed my
5 name to this specification on this 18 day of
May A. D. 1927.

CORNELIS FRANCISCUS MARIA van BERKEL.
